(57) CLAIM

The ornamental design for an organizing grid for storage case as shown and described.

DESCRIPTION

FIG. 1 is a left, front, top perspective view of the organizing grid for storage case;
FIG. 2 is a front elevation view of the organizing grid for storage case;
FIG. 3 is a rear elevation view of the organizing grid for storage case;
FIG. 4 is a left elevation view of the organizing grid for storage case;
FIG. 5 is a right elevation view of the organizing grid for storage case;
FIG. 6 is a top view of the organizing grid for storage case;
FIG. 7 is a bottom view of the organizing grid for storage case;
FIG. 8 is a left, front, top perspective view of a second embodiment of the organizing grid for storage case;
FIG. 9 is a front elevation view of the second embodiment;
FIG. 10 is a rear elevation view of the second embodiment;
FIG. 11 is a left elevation view of the second embodiment;
FIG. 12 is a right elevation view of the second embodiment;
FIG. 13 is a top view of the second embodiment;

FIG. 14 is a bottom view of the second embodiment;
FIG. 15 is a left, front, top perspective view of a third embodiment of the organizing grid for storage case;
FIG. 16 is a front elevation view of the third embodiment;
FIG. 17 is a rear elevation view of the third embodiment;
FIG. 18 is a left elevation view of the third embodiment;
FIG. 19 is a right elevation view of the third embodiment;
FIG. 20 is a top view of the third embodiment;
FIG. 21 is a bottom view of the third embodiment;
FIG. 22 is a left, front, top perspective view of a fourth embodiment of the organizing grid for storage case;
FIG. 23 is a front elevation view of the fourth embodiment;
FIG. 24 is a rear elevation view of the fourth embodiment;
FIG. 25 is a left elevation view of the fourth embodiment;
FIG. 26 is a right elevation view of the fourth embodiment;
FIG. 27 is a top view of the fourth embodiment;
FIG. 28 is a bottom view of the fourth embodiment;
FIG. 29 is a left, front, top perspective view of a fifth embodiment of the organizing grid for storage case;
FIG. 30 is a front elevation view of the fifth embodiment;
FIG. 31 is a rear elevation view of the fifth embodiment;
FIG. 32 is a left elevation view of the fifth embodiment;
FIG. 33 is a right elevation view of the fifth embodiment;
FIG. 34 is a top view of the fifth embodiment;
FIG. 35 is a bottom view of the fifth embodiment;
FIG. 36 is a left, front, top perspective view of a sixth embodiment of the organizing grid for storage case;
FIG. 37 is a front elevation view of the sixth embodiment;
FIG. 38 is a rear elevation view of the sixth embodiment;
FIG. 39 is a left elevation view of the sixth embodiment;
FIG. 40 is a right elevation view of the sixth embodiment;
FIG. 41 is a top view of the sixth embodiment;
FIG. 42 is a bottom view of the sixth embodiment;
FIG. 43 is a left, front, top perspective view of a seventh embodiment of the organizing grid for storage case;
FIG. 44 is a front elevation view of the seventh embodiment;
FIG. 45 is a rear elevation view of the seventh embodiment;
FIG. 46 is a left elevation view of the seventh embodiment;
FIG. 47 is a right elevation view of the seventh embodiment;
FIG. 48 is a top view of the seventh embodiment; and,
FIG. 49 is a bottom view of the seventh embodiment.

The shade lines in the Figures show contour and not surface ornamentation.

The evenly spaced broken lines and the unshaded areas within them in FIGS. 1-49 showing portions of the organizing grid for storage case are included for the purpose of illustrating environment that do not form a part of the claimed design. Additionally, the dot-dash-dot broken lines in any of the figures depict the boundaries of the claim that form no part thereof.
